UNITED STATES PATENT OFFICE

2,470,194

BURN-IN TOOL

Charles Roadnan Terry, Tulsa, Okla.

Application January 23, 1948, Serial No. 3,932

1 Claim. (Cl. 219—21)

1

This invention relates to new and useful improvements and structural refinements in so called burn-in tools such as are commonly employed by furniture workers, carpenters, or the like for applying hard varnish, filling in cracks, and for similar other purposes, and the principal object of the invention is to provide a device of the character herein described, wherein the temperature of the burning blade may be easily and conveniently controlled.

Conventional burn-in tools usually derive their source of heat from an electric element with which they are provided, the heat from this element being conducted directly to the tool blade. As a result, the blade often becomes heated to an excessive temperature so that the supply of current to the electric element must be temporarily discontinued, which procedure of course, involves not only inconvenience to the workmen, but also, a considerable loss of time.

It is, therefore, a further object of the invention to eliminate this disadvantage by providing, as aforesaid, a burn-in tool equipped with means for varying thermal conductivity between the heating element and the working blade.

Another object of the invention is to provide a burn-in tool which is simple in construction, which may be easily and conveniently manipulated, which will not easily become damaged, and which will readily lend itself to economical manufacture.

With the above more important objects in view and such other objects as may become apparent as this specification proceeds, the invention consists essentially of the construction and arrangement of parts as shown in the accompanying drawings in which:

Figure 1 is a top plan view of the invention.

Figure 2 is a side elevational view thereof, showing the same in position for maximum thermal conductivity.

Figure 3 is a side elevational view, similar to that shown in Figure 2, but illustrating the invention in position for reduced thermal conductivity, and

Figure 4 is a cross sectional view, taken substantially on the plane of the line 4—4 of Figure 2.

Like characters of reference are employed to designate like parts in the specification and throughout the several views.

Referring now to the accompanying drawings in detail, the invention consists of a burn-in tool designated generally by the reference character 10, the same embodying in its construction a suitable shank 11 provided at one end thereof with

2

a handle 12, while the remaining end portion 13 of the shank contains a suitable heating unit, such as for example, as electric heating element 14.

If desired, the heating unit 13 may be formed separately from the shank 11 and may be secured thereto by means of suitable straps 15 and fastening bolts or rivets 16.

An applicator blade or burn-in blade 17 is secured at one end thereof to the shank 11 by one of the bolts 16, this blade being heated by the unit 13 and in conventional tools, being disposed immediately adjacent to and in contact with the heating unit, so as to assure the utmost thermal conductivity between the heating unit and the blade.

However, the essence of novelty in the invention resides in provision of means for varying the thermal conductivity between the unit 13 and the blade 17, this being accomplished by providing an adjusting screw 18 in the unit 13, which screw is engageable with the free end portion of the blade 17, substantially as shown.

It should be understood that the blade 17 is of a resilient nature, normally being urged by its inherent resiliency in contact with the adjacent strap 15 of the heating unit 13. This is best shown in the accompanying Figure 2, wherein it will be apparent that maximum amount of thermal conductivity will exist between the heating unit 13 and the blade 17, since the parts are in contact.

However, when it is desired to decrease the thermal conductivity between the heating unit 13 and the blade 17, the adjusting screw 18 is simply tightened so that by its engagement with the blade 17, the latter is forced, against its resiliency, from the adjacent strap 15. Accordingly, a space will exist between the blade 17 and the adjacent strap 15 of the heating unit 13 and thermal conductivity will thus be retarded. Moreover, by increasing or decreasing the space between the blade 17 and the adjacent strap 15, the extent of thermal conductivity may be varied as desired.

Needless to say, the element 14 receives its supply of current through the medium of a suitable conductor 19 which extends outwardly through the handle 12, as will be clearly apparent.

It is believed that the advantages and use of the invention will be clearly understood from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

In a burn-in tool, the combination of a heated shank, a resilient work engaging blade secured at one end thereof to said shank and disposed at one side of the latter, said blade being urged by its resiliency in contact with the side of said shank but being adjustable from a position where a major portion of its length contacts said shank to a variably spaced position relative thereto, and means for adjusting said blade comprising a screw

extending transversely through said shank and having an end thereof engageable with said blade for pressing a major portion of the blade out of contact with said shank to a variably spaced position relative thereto.
